(57) **CLAIM**

The ornamental design for an infant carrier shroud, as shown and described.

DESCRIPTION

FIG. 1 is a front unfolded view of an infant carrier shroud showing my new design;

FIG. 2 is a left side view thereof, the right side view being a mirror image thereof;

FIG. 3 is a bottom view thereof;

FIG. 4 is a top view thereof; and,

FIG. 5 is a moved view thereof showing the extensions of the shroud in a folded position.

1 Claim, 2 Drawing Sheets
